UNITED STATES PATENT OFFICE

ARTHUR J. MUNDY, OF BOSTON, MASSACHUSETTS, ASSIGNOR TO SUBMARINE SIGNAL COMPANY, OF WATERVILLE, MAINE, A CORPORATION OF MAINE.

SOUND TRANSMITTER AND RECEIVER.

No. 921,141.

Specification of Letters Patent. Patented May 11, 1909.

Application filed April 23, 1902. Serial No. 104,295.

To all whom it may concern:

Be it known that I, ARTHUR J. MUNDY, of Boston, in the county of Suffolk and State of Massachusetts, a citizen of the 5 United States, have invented a new and useful Improvement in Sound Transmitters and Receivers, of which the following is a full, clear, and exact description, reference being had to the accompanying drawings, 10 forming a part of this specification, in explaining its nature.

This invention is allied with that described in Letters Patent No. 868,880 dated October 27, 1907, which describes an electrical sound transmitter and receiver for use in transmitting sound vibrations of signals or articulate speech and which comprises a pair or series of transmitters preferably arranged for joint action. In the 20 present invention I have represented the employment of a transmitter of this organization although I do not confine myself to such type of transmitter so far as concerns the essential element of this invention. 25 With the transmitter specified, or with any other, I have combined what I term a focusing diaphragm or shell. This focusing diaphragm or shell bears such relation to the transmitter that it serves to receive the 30 sound vibrations from the sound-transmitting medium, whether water, air or other substance, and focuses them or a part of them upon the diaphragm, or the diaphragms if there be more than one, of the 35 electrical transmitter. The shell may also serve to protect the electrical transmitters from the surrounding medium, water for instance, and may also serve to conduct vibrations to the diaphragms and the means for 40 varying the electrical resistance by what may be called molecular action as distinguished from the vibration of a diaphragm. I prefer to employ a shell or focusing diaphragm which is spherical in shape and to 45 make the same of thin brass, but I do not confine myself to this shape or to this material. In use it receives the sound vibrations from the medium with which it is in contact, be it water or air, and focuses them 50 upon the interior diaphragms and also molecularly communicates them to the means for varying the electrical resistance with which it has connection.

I will now describe the invention in connection with the drawing forming a part

of this specification where the figure shows the transmitter partly in side elevation and partly in central section. The transmitter is represented as submerged in water.

Referring to the drawings:—A represents 60 the complete transmitting device consisting of the electrical transmitter B, which may be of any suitable construction. It is represented as centrally located in the focusing shell C, which also acts as a guard or protector. The diaphragms of the transmitter are vertically disposed within the focusing shell, and the shape of that portion of the shell in front of the diaphragms is such as to form a sound-refracting means which 70 serves to deflect the sound vibrations received by it from a straight line to one which focuses them upon the diaphragms much as rays of light are focused by a lens. The capacity of each diaphragm is thereby 75 very considerably increased and the intensity of the sound vibrations delivered upon or against it also increased and multiplied toward the center of the diaphragm thereby 80 still further amplifying their vibratory power or effect upon the diaphragm and increasing its power. The shell may also 85 serve as a protector for the transmitter and a shield for its diaphragm or diaphragms and thus tends to keep the physical condition of the diaphragm constant under all 90 circumstances as well as the conditions of its use. It is desirable where the transmitter is employed for submarine signaling and is submerged in water that it be protected 95 from injury by the water by being contained in a watertight casing. It is also desirable for some submarine uses that the diaphragm of the transmitter be not affected by variations which might affect it were it exposed 100 to the water, such, for instance, as those arising from variations in the specific gravity or density of the water and by shielding the diaphragms so that the water may not come in contact therewith and that they may 105 be maintained in a uniform condition at whatever depth the transmitter may be submerged. Any loss in effectiveness due to the fact that such a shield holds the water from the diaphragm or diaphragms so that it or they do not receive their vibratory power directly from the medium which transmits it is partially overcome because of 110 the sound-focusing effect obtained by the shield or case, and because also of the effect

occasioned by the molecular transfer of vibrations from the case to the means for varying electrical resistance which occurs to a greater degree when the transmitter is mounted in part upon the case as well as upon the diaphragm. I have represented in the drawings the employment within the spherical case of a transmitting apparatus comprising two transmitters in electrical connection in series with a duplex receiver. As I do not herein claim the specific construction of the transmitter and as any other transmitter may when so combined with the focusing and protecting shell or case be used, it is unnecessary for me to further describe its construction. It has a neck *b* which passes through the shell and affords means whereby it is attached to the shell and suspended within its chamber. Its electrical connections pass through this neck and an insulating suspending device to the duplex receiver *D*.

I have shown the spherical case as made in the three parts *a*, *a'*, *a''*. *a* is the central division and has annular screw flanges *a*³, *a*⁴ upon its inner side and which are adapted to receive and hold the screw flanges *a'*⁵, *a''*⁶, respectively, at the sections *a'*, *a''*. Such gaskets as may be necessary for preventing leakage at the joints are employed.

It will be observed that the transmitter is represented as suspended in the shell in such a manner as to present its diaphragms in a vertical plane; also, that all parts of the transmitter, including the diaphragm, are focused with respect to the shell; in other words, the shell being spherical, focuses sound vibrations from all directions to the center of the sphere and thus the top and bottom of the transmitter are provided with sound focusers as well as the diaphragms, and this is of advantage because of the peculiarity or characteristics of waves of sound which not only have a longitudinal to and fro motion, but also varying pressure at any point in all directions. It will further be seen that this disposition of the sound focusers permits the transmitter to receive equally well sounds coming from either direction. Especially is this true with the structure which employs vibratory diaphragms in line with each other and oppositely faced.

The shell and transmitter are represented as suspended by means of a flexible suspending cord which does not govern the position of the shell or transmitter and no means are necessary for so governing them as they have what may be termed a universal power of receiving sound impulses from any direction and however their position may be with regard to them.

Having thus fully described my invention, I claim and desire to secure by Letters Patent of the United States:—

1. An electric sound transmitter and a refracting sound focuser, arranged in relation to the diaphragm of the transmitter to focus sound vibrations thereon.

2. A sound receiving instrument comprising a transmitter and a sound focusing liquid tight inclosure for the same.

3. A sound receiving instrument comprising a transmitter and a diaphragm having a refracting focusing surface continuous across the face of the transmitter.

4. A sound receiving instrument comprising an upright transmitter and a protecting plate therefor, continuous in a vertical plane, said plate being shaped to focus sound waves refracted through upon the transmitter.

5. A sound receiving instrument comprising a transmitter and a refracting sound focuser therefor, said focuser acting to shield the transmitter over a considerable are.

6. An electric sound transmitter having a number of co-acting diaphragms and a refracting sound focuser for each diaphragm to focus sound vibrations thereon.

7. An electric sound transmitter having a number of co-acting vertical diaphragms and a watertight sound focuser for each diaphragm arranged in relation to it to focus sound vibrations thereon.

8. An electric sound transmitter having a number of co-acting sound-receiving diaphragms and a combined sound focuser and watertight shield for each diaphragm arranged in relation to it to focus sound vibrations upon it and also to protect it from physical injury.

9. A sound-transmitting device comprising a closed sphere, one or more sections of which act as a sound focusing instrumental- 105 ity and an electric transmitter contained in the sphere and having a diaphragm in a focusing relation to the shell of the sphere.

10. A sound-transmitting device comprising a sphere, sections of which act as sound-focusing instrumentalities, and a multiple electric transmitter contained in the cavity of the shell with its diaphragms in focusing relation to the sound-focusing sections of the shell.

11. A sound-transmitting device comprising a sphere, sections of which act as sound-focusing instrumentalities, and a multiple electric transmitter suspended by a single connection within the shell and having sound-receiving diaphragms oppositely and vertically arranged to face the walls of the shell.

12. A vertically disposed electric sound transmitter and a sound refracting focuser arranged in relation to the transmitter to focus sound vibrations on the side of the transmitter.

13. A vertically disposed electric sound transmitter and a sound focuser arranged

in relation to the transmitter to focus sound vibrations on the bottom of the transmitter.

14. A vertically disposed electric sound transmitter and a sound focuser arranged in relation to the transmitter to focus sound vibrations on the top of the transmitter.

15. An electric sound transmitter and a refracting sound focuser arranged in relation to the transmitter to focus sound vibrations on two or more sides or parts thereof.

16. An electric sound transmitter and a refracting sound focuser arranged in relation to the transmitter to focus sound vibrations on a diaphragm of the transmitter and also upon a side of the transmitter.

17. An electric sound transmitter and a sound focuser arranged in relation to the transmitter to focus sound vibrations on any part thereof.

20 18. An electric sound transmitter and a sound focuser arranged in relation to the transmitter to focus sound vibrations upon all parts of the transmitter and to shield the same.

25 19. An electric sound transmitter and inclosing sound focusers oppositely arranged in relation to each other and to the transmitter whereby sound vibrations from either direction are caused to be focused upon the transmitter.

30 20. An electric sound transmitter and a universal sound focuser arranged in relation

to the transmitter to focus sounds thereon coming from any direction and without changing its position.

35

21. An electric sound transmitter and inclosing sound focusers oppositely arranged in relation to each other and to the transmitter whereby sound vibrations from either direction are caused to be focused upon the transmitter and without changing the position of the transmitter.

40

22. An electric sound transmitter having a number of sound receiving diaphragms, vertically arranged, and an inclosing sound focuser for each diaphragm, the focusers and transmitter being free to move or turn upon or about a substantially vertical axis.

45

23. An electric sound transmitter having a tuned diaphragm and an inclosing sound focuser to focus sound vibrations thereon.

50

24. A suspended electric sound transmitter comprising a suspending means, a closed shell, one or more sections of which form a sound-focusing means, and an electric transmitter contained in the shell, having one or more diaphragms bearing a focusing relation to the focusing section or sections of the shell.
